UNITED STATES PATENT OFFICE.

ALFRED HOSKING, OF AUCKLAND, NEW ZEALAND.

TELLURIAN.

SPECIFICATION forming part of Letters Patent No. 776,911, dated December 6, 1904.

Application filed October 13, 1903. Serial No. 176,883. (No model.)

To all whom it may concern:

Be it known that I, ALFRED HOSKING, a subject of the King of Great Britain, and a resident of Auckland, New Zealand, have invented 5
a new and Improved Tellurian, of which the following is a full, clear, and exact description.

The object of the invention is to provide a new and improved tellurian which is simple and durable in construction, easily manipulated, and arranged for demonstrating or illustrating the relative motions of the earth and moon around the sun.

The invention consists of novel features and parts and combinations of the same, as will be more fully described hereinafter and then pointed out in the claims.

A practical embodiment of the invention is represented in the accompanying drawings, forming a part of this specification, in which 20 similar characters of reference indicate corresponding parts in all the views.

Figure 1 is a side elevation of the improvement. Fig. 2 is a sectional plan view of the same on the line 2 2 of Fig. 1. Fig. 3 is an 25 end view of the same. Fig. 4 is an enlarged sectional side elevation of the suspending mechanism for the representation of the moon, and Fig. 5 is an enlarged view of the adjustable ring with the markings thereon.

On the upper end of a suitably-constructed standard A is arranged the representation B of the sun, and on the said standard is mounted to swing or turn horizontally an arm C, provided at one end with a handle C', adapted to 35 be taken hold of by the demonstrator for swinging the arm C around on the standard A as the axis. On the free end of the arm C is mounted to turn a globe D, representing the earth and having a vertically-disposed shaft D', journaled in suitable bearings on the free end of the said arm C, and on the shaft D' is fastened a bar D'', in which is journaled the axis D''' of the globe, as will be readily understood by reference to Fig. 1.

On the shaft D' of the globe is secured a 45 sprocket-wheel E, connected by a sprocket-chain E' with a sprocket-wheel E'', fixed on the standard A, so that when the arm C is swung around by the demonstrator the chain E' rolls off the fixed sprocket-wheel E'', and

consequently turns the sprocket-wheel E and the globe D, the center of which lies in a horizontal plane extending through the center of the representation of the sun B.

As shown in the drawings, the sprocket-wheel E'' has one more tooth than the sprocket-wheel E, so as to cause a rotation of the globe D in such a manner as to illustrate the precessional motion of the earth.

On the free end of the arm C is arranged a cross having a transverse arm C² and a longitudinal arm C³, and on the terminals of the said arms C² and C³ is mounted a frame F, having a transverse U-shaped bar F' extending around the globe diametrically in a transverse direction, and the upper end of the bar F' is joined by the upper end of a bar F'', rising from the arm C³ and standing at right angles to the bar F'. The center of curvature of the curved portions of the bars F' or F'' 70 coincides with the center of the globe, as will be readily understood by reference to the drawings.

Near the upper end of the bar F'' is fulcrumed the lug G' of an arm G, connected at its free 75 end by a universal joint H with the representation of the moon I, having a semispherical hood I', and one half portion of the moon is silvered and the other half portion is blackened. The hood I' is used to conceal that half portion of the moon which is turned from the earth, (represented by the globe D,) while the silvered half portion of the representation of the moon I is always turned toward the representation of the sun B.

The representation of the moon I is adapted to be manually rotated on its axis, and consequently during the revolution of the moon it gradually assumes such position relative to the hood that the latter covers the half of the moon farthest from the representation of the earth, and consequently a full moon is illustrated. By continuing the revolution of the representation of the moon the hood eventually conceals the side of the moon nearest the sun, and thus a new moon is represented.

The universal joint H consists, preferably, of a rod H', extending centrally through the moon I and the hood I' for both the moon and the hood to be turned loosely on the rod by 100

the operator, and on the upper end of the rod H' is formed or secured a half-sphere H², seated in a correspondingly-shaped socket G², formed on the free end of the arm G, the said rod H' extending through a slot in the socket for suspending the moon perpendicularly at all times.

The lug G' of the arm G is connected by a link J and a clamping-screw J' with the slotted portion F³ of the bar F² to allow of adjusting the arm G up or down to any angle with the plane of the ecliptic, as the demonstrator may desire.

On the arm C is fixed a pointer K, showing the spot on the earth where the direct rays of the sun fall, as will be readily understood by reference to Fig. 1. On the arm C and on diametrically opposite sides of the sprocket-wheel E² are arranged pointers L and L', indicating over an adjustable ring N, held on the standard A and on which, as shown in Fig. 5, are marked the months of the year, the equinoxes, the solstices, and the signs of the zodiac, so that the pointer L' indicates the time of the year, while the pointer L indicates the position of the sun in the zodiac.

The lines 21 and 23 shown on the months of March and September indicate the equinoxes, and the lines 21 shown on the months of June and December indicate the solstices.

Having thus described my invention, I claim as new and desire to secure by Letters Patent—

1. A tellurian provided with a pivoted arm, a globe mounted to turn on the said arm on swinging the latter around, a cross at the free end of the arm, a frame rising from the said cross, a supporting-arm carrying a representation of the moon and pivoted on the said frame, and means for adjusting the supporting-arm on the frame to any desired angle with the plane of the ecliptic.

2. A tellurian provided with a pivoted arm, a globe mounted to turn on the said arm on swinging the latter around, a frame on the free end of the said arm, an angular supporting-arm for carrying a representation of the moon, pivoted on the said frame, and means for adjusting the said angular supporting-arm on the frame, the said means comprising a link pivotally connected with the angular arm and a clamping-screw for connecting the link with the slotted portion of the said frame, as set forth.

3. A tellurian provided with a representation of the moon, a supporting-arm for the representation of the moon, a hood for the said representation of the moon, and a universal joint for suspending the said representation of the moon from the said arm, the said universal joint comprising a rod extending through the representation of the moon and through the hood, and on which the moon and hood can be turned by the operator, and a half-sphere on the upper end of the rod and engaging a corresponding - shaped socket formed on the end of the arm, the socket hav-

ing a slot through which the arm extends, as set forth.

4. A tellurian having an arm mounted to swing around and provided at its terminal with a cross, a globe mounted to turn on the terminal of the said arm, and a frame erected on the said cross and consisting of a transverse bar and a longitudinal bar jointed at its top to the top of the cross-bar, the center of curvature of the curved portions of the said bars coinciding with the center of the said globe, as set forth.

5. A tellurian comprising a standard carrying a representation of the sun, a manually-controlled arm mounted to turn on the said standard, a globe mounted to turn on the free end of the said arm, a gearing between the said standard and the shaft of the globe to rotate the latter, a frame on the free end of the said arm, a supporting-arm for carrying a representation of the moon, the said arm being provided with a lug fulcrumed on the said frame and a link connected with the said lug and adjustably connected with the said frame, as set forth.

6. A tellurian, comprising a standard supporting a representation of the sun, a manually-controlled arm mounted to turn on the standard, a globe mounted to turn on the free end of the arm, a gearing between the said standard and the shaft of the globe to rotate the latter when the arm is turned, a frame on the free end of said arm, a supporting-arm for carrying a representation of the moon and pivoted on the said frame, a pointer fixed on the said manually - controlled arm to show where the direct rays of the sun fall on the globe, an adjustable ring held on the standard and having marked thereon the months of the year, the equinoxes, the solstices and the signs of the zodiac, and pointers carried by the arm and indicating over the adjustable ring at diametrically opposite points, as set forth.

7. A tellurian comprising a standard supporting a representation of the sun, a sprocket-wheel fixed on the said standard, a manually-controlled arm mounted to swing on the standard, and provided at one end with a handle, a globe having a vertically - disposed shaft mounted to turn in the free end of said arm, a sprocket-wheel secured on the said shaft and having one tooth less than the sprocket-wheel on the said standard, a sprocket-chain connecting the sprocket - wheels with each other, an adjustable ring held on the standard and on which are marked the months of the year, the equinoxes, the solstices and the signs of the zodiac, and pointers arranged on the arm on diametrically opposite sides of the sprocket-wheel on the standard and indicating on the said adjustable ring, as set forth.

8. A tellurian comprising a standard carrying a representation of the sun, a manually-controlled arm mounted to turn on the said

standard, a globe mounted to turn on the free end of the said arm, a gearing between the standard and the shaft of the globe, a frame on the free end of the said arm and comprising a transverse U-shaped bar extending around the globe, and a bar standing at right angles to the U-shaped bar and connected at its upper end to the top of said transverse bar, and a supporting-arm for carrying a representation of the moon, the said arm being fulcrumed to the last-mentioned bar near its junction with the transverse bar, and means for adjusting the said supporting-arm.

9. A tellurian, comprising a standard supporting a representation of the sun, a sprocket-wheel fixed on the said standard, a manually-controlled arm mounted to swing on said standard and provided at one end with a han-

dle, a globe mounted to turn on the free end of the said arm, a sprocket-wheel secured on the shaft of the globe and having one tooth less than the sprocket-wheel on the standard, a sprocket-chain connecting the sprocket-wheels with each other, a frame carried at the free end of the arm, and a supporting-arm carrying a representation of the moon and adjustably connected with the said frame, as set forth.

In testimony whereof I have signed my name to this specification in the presence of two subscribing witnesses.

ALFRED HOSKING.
